UNITED STATES PATENT OFFICE.

ARON M. BEAM, OF DENVER, COLORADO, ASSIGNOR TO THE AMERICAN CONTINUOUS RETORT COMPANY, OF DENVER, COLORADO, A CORPORATION OF COLORADO.

POWER-TRANSMITTING RECIPROCATIVE-MOVEMENT MECHANISM.

1,371,340.

Specification of Letters Patent. Patented Mar. 15, 1921.

Original application filed February 17, 1920, Serial No. 359,435. Divided and this application filed March 22, 1920. Serial No. 367,973.

To all whom it may concern:

Be it known that I, ARON M. BEAM, a citizen of the United States of America, residing at the city and county of Denver and 5 State of Colorado, have invented a new and useful Power-Transmitting Reciprocative-Movement Mechanism, of which the following is a specification.

My invention relates to a new and improved type of power transmitting reciprocative movement mechanism, and the objects of my invention are:

First. To provide a thoroughly practical and easily operating reciprocating mechanism having power enough to operate several different and independent reciprocating mechanisms simultaneously.

Second. To provide a geared form of power transmitting reciprocal movement actuating mechanism that can be arranged in units of one, two or more mechanisms, that can all be operated simultaneously from one source of rotative power.

Third. To provide an easily constructed, simple and powerful reciprocative movement mechanism that is inexpensive to manufacture and is easily and quickly applied to retort furnaces for roasting ore and oil shales that have a number of retorts with ore rabbling and scraper mechanisms in them, and that can also be applied to multiple deck ore driers and to other machines that use mechanisms that move reciprocally.

I attain these objects by the mechanism illustrated in the accompanying drawings, in which:

Figure 1 is a side elevation of the improved power transmitting reciprocating movement mechanism.

Fig. 2 is a front view thereof.

Fig. 3 is a side elevation of a series of the mechanism shown in Fig. 1, and connected to operate in unison; and

Fig. 4 is a horizontal sectional view on the line 4-4 of Fig. 1.

Similar letters of reference refer to similar parts throughout the several views.

Referring to the drawings:

The numeral 1 designates the frame work 50 of a reciprocating mechanism embodying my invention. In this view, the numeral 2, designates the back plate, and the numerals 3 and 4, designate cast brackets that form the lower and upper ends of the frame, and

at the inner and outer ends of these brackets 55 I place vertical cast iron standards 5 and 6, that are secured to the brackets at their upper and lower ends, thus forming a stationary square shaped supporting frame having a large clear space through it between its 60 side and end members, for the moving parts of my power transmitting, reciprocating mechanism, the weight of which may be supported on any suitable support, such as a brick pier 6A.

The upper and lower brackets and the inner vertical standard are securely bolted to the back plate 2, which member is used to secure the reciprocating mechanism to a machine of any kind where it is desired to 70 use a reciprocating movement, to drive reciprocally any part of it. This back plate can be dispensed with if it is not needed.

The opposite ends of the upper and lower brackets are provided with depending lugs 75 7 and 8, that extend into the recesses 9 and 10, that are formed by the opposing side standards 5 and 6, to receive them. These lugs are provided with apertures through which rods 11 and 12, are slidably mounted. 80 To these rods I secure the upper ends of a reciprocating frame 13, that is positioned in a vertical plane between the upper and lower brackets. These rods are secured to the opposite ends of the frame 13, preferably by extending the rods through long lugs 14 that are formed at its opposite ends, and securing them in any desired adjusted position by set screws 15. Consequently, 85 these upper and lower rods are slidably secured in the lugs 7 and 8, of the brackets, and are rigidly secured in adjusted positions to the vertical frame, and when this frame 13, is reciprocated, the rods reciprocate with it.

To the center of the height of this reciprocating frame, a third rod 16, is secured to a hub 17, that is formed on the adjacent side of the reciprocating frame and it, as well as the upper and lower rods, extends through 100 apertures 18, that are formed through the back plate 2, and they can also be further supported by additional bearing devices on the machine to which my reciprocal movement is applied, and if desired, they can be 105 slidably supported in sleeves 19, as shown in my pending application for a patent for a multiple retort ore and oil shale roasting

furnace, filed February 17th, 1920, Serial No. 359,435, of which this application is a divisional part, and in which application my present reciprocating mechanism is shown 5 as the reciprocating power driving mechanism that reciprocates the ore rabbling and scraper mechanism of the several retorts of the ore roasting furnace of that application.

While I have shown three rods in my 10 present application being attached to and consequently reciprocated by the reciprocating frame, I desire it understood that the center rod can be dispensed with if desired, or that one or two or more rods can be attached to any predetermined part of the 15 height of the reciprocating frame. The upper and the lower rods are essential to the support of the reciprocal frame which is mounted on them, but they can be used just 20 the same for imparting a reciprocal movement to any machine part or combination of parts to which they may be attached, that requires such a movement, as in the furnace application above referred to, but there may 25 be machines that will require one or two or more rods positioned at and extending from different points of the vertical height of the reciprocating frame than I have shown in the drawings of this application.

30 This vertically positioned reciprocating frame 13, comprises a casting, and it contains a vertically arranged slot 20, the opposite sides of which are machined to receive slidably a cross-head 21, that is made 35 in two equal halves which are bolted together by bolts 22.

This cross head contains a central aperture that is bored to fit on the crank pin 23, of a crank shaft 24, that is journaled in 40 bearings 25, that are secured upon brackets 25^A, that are bolted to the opposing sides of the standards 5 and 6. This crank shaft extends beyond the bearings 25, and on one 45 of its ends a gear wheel 26, is secured. This gear wheel meshes with a gear pinion 27, that is secured to one end of a counter shaft 28, that is journaled in bearings 29, that are secured to brackets 30, that are formed on the outside faces of the outer standards 6, 50 and a belt pulley 31, or if preferred, a sprocket wheel, is secured on the opposite end of this countershaft and can be connected to any suitable source of rotative power by which the countershaft can be rotated to cause its gear pinion to rotate the gear wheel on the crank shaft, and consequently the crank shaft, which causes the crank pin of the crank shaft to reciprocate 55 the cross head in the vertical slideway in the reciprocating frame 13, and this action 60 will reciprocate the vertical frame 13, and the upper and lower rods 11 and 12, in the lugs of the brackets, and also the central rod 16, all three rods moving in the same reciprocal direction, and all at the same time, and 65

the reciprocal frame moves reciprocally between the four vertical side standards 5 and 6.

If desired, two or three or more of these power reciprocating mechanisms can be arranged one above the other, as shown in outline in Fig. 3, in which they can be driven from the pinion shaft of one of the reciprocating mechanisms by connecting the pinion shafts of the other two mechanisms by 70 sprocket wheels 32, and chains 33, as shown in this figure, in which case the rotative power receiving pulley 31, can be applied to the pinion shaft of either one of the two or three or more reciprocating mechanisms. 80

When two or more of my reciprocating movement mechanisms are used one above the other, a supporting block 34, is placed between them and is secured to them and to the back plate 2.

When described my invention, what I claim and desire to secure by Letters Patent, is:

1. In a reciprocating movement mechanism, the combination of the stationary supporting frame, with a reciprocating movement frame slidably mounted in said stationary frame, means including a crank 95 shaft for imparting a reciprocating movement to said reciprocating movement frame, said stationary frame consisting of a lower and an upper bracket, and standards placed between their opposite ends, said brackets being secured to said standards, and a plate secured to the large end of said brackets and to the adjacent standards.

2. In a reciprocating movement mechanism, the combination of the stationary supporting frame, with a reciprocating movement frame slidably mounted in said stationary frame, means including a crank shaft for imparting a reciprocating movement to said reciprocating movement frame, said reciprocating frame being provided with a reciprocating cross head connected to the said crank shaft, said reciprocating movement frame being provided with rods adapted to be connected to mechanism requiring a reciprocating movement, said stationary frame comprising lower and upper brackets, and standards between their opposite ends, the opposite ends of said standards being provided with recesses, lugs on 110 said brackets projecting into the recesses of said standards, said lugs being provided with apertures in which the said rods of said reciprocating frame are slidably mounted.

3. In a reciprocating movement mechanism, the combination of the stationary supporting frame, with a reciprocating movement frame slidably mounted in said stationary frame, means including a crank shaft for imparting a reciprocating movement to said reciprocating movement frame, said reciprocating frame being provided with a reciprocating cross head connected to the said crank shaft, said reciprocating movement frame being provided with rods adapted to be connected to mechanism requiring a reciprocating movement, said stationary frame comprising lower and upper brackets, and standards between their opposite ends, the opposite ends of said standards being provided with recesses, lugs on said brackets projecting into the recesses of said standards, said lugs being provided with apertures in which the said rods of said reciprocating frame are slidably mounted, and a rod secured to the central portion of said reciprocating frame, said reciprocating frame being slidably supported by the rods extending slidably through the lugs of said brackets.

4. In a reciprocating movement mechanism, the combination of the stationary supporting frame, with a reciprocating movement frame slidably mounted in said stationary frame, means including a crank shaft for imparting a reciprocating movement to said reciprocating movement frame, a gear wheel on said crank shaft, a counter shaft journaled to the outer standard, a gear pinion on said counter shaft in

mesh with said gear wheel, means for rotating said gear wheel, means for connecting two or more reciprocating movement mechanisms together and for driving them from the pinion shaft of either one of said mechanisms.

5. In a reciprocating movement mechanism, the combination of the stationary supporting frame, with a reciprocating movement frame slidably mounted in said stationary frame, means including a crank shaft for imparting a reciprocating movement to said reciprocating movement frame, a gear wheel on said crank shaft, a counter shaft journaled to the outer standard, a gear pinion on said counter shaft in mesh with said gear wheel, means for rotating said gear wheel, means for connecting two or more reciprocating movement mechanisms together and for driving them from the pinion shaft of either one of said mechanisms, said means comprising sprocket wheels on said pinion shafts and sprocket chains connecting said sprocket wheels together, a plate secured to the opposite ends of said brackets from said countershaft, provided with apertures arranged to receive and support slidably the rods projecting from said reciprocating movement power transmitting frame.

In testimony whereof I affix my signature in presence of two witnesses.

ARON M. BEAM.
